PROCESS OF MAKING DIPHENYL

Application filed January 9, 1930. Serial No. 419,659.

This invention relates to an improvement in a method and apparatus for making diphenyl from benzol by thermal synthesis, and has for its object to provide for increased 5 yields of diphenyl and economies in the heat requirements for such a process.

A further object of our invention is to provide a process and apparatus of the character 10 designated wherein the occurrence of side reactions and the production of tar and carbon is minimized.

It has recently been discovered that diphenyl in commercial quantities may be made by passing benzol through a bath of 15 molten metal such as lead. In the operation of this process on a large scale we have encountered difficulties which are inherently connected with such large-scale operation, and which only became apparent when such 20 large-scale factory operations were undertaken.

The difficulties which were thus encountered were the following:—We have found that when heating large containers of molten 25 metal to temperatures in the neighborhood of the diphenyl formation temperature, namely, between 600° C. and 850° C., the hydrostatic head of metal caused strains to be set up in the metal containers which finally 30 caused leaks and loss of metal, with considerable monetary loss. Furthermore, with metals there is always the danger of alloys being formed which will further weaken the metal container.

These difficulties have been overcome by our discovery that certain molten salts could be used in place of the molten lead or other metal without subjecting the container to dangerous strains at high temperatures and 35 without alloys being formed between the metal of the bath and the metal container. We have further found that, in general, molten salts do not accelerate carbon formation as do metals, and hence have been able 40 to so modify our procedure as to prevent a considerable loss through decomposition of the benzol used.

The salts which we have found workable are calcium chloride, mixed with sufficient 45 sodium chloride so that its melting point is

lowered to the neighborhood of 600° C. We have found that a mixture of 28% sodium chloride and 72% calcium chloride is particularly well suited for this work, since it has a low melting point. Other salts which 55 we have used are sodium meta-phosphate, or sodium pyrophosphate, which on heating to the diphenyl temperature change to sodium meta-phosphate. We have also used a mixture of 50% of sodium carbonate and potassium chloride, with satisfactory results. All 60 of these salts have densities substantially less than 2.5 at ordinary temperatures, which is further decreased on heating and melting.

As a result of the use of molten salts in 65 place of molten metals, we have obtained higher yields of diphenyl in our process. We believe that these higher yields are due to the fact that the differences in density between the molten salt and the benzol vapor is 70 less than the difference in density between the molten metal such as lead, and the benzol vapor. This lesser difference in density permits the vapor to remain longer in contact with the salt and hence permits a nearer 75 approach to the chemical equilibrium to be attained.

While we do not at present understand the exact mechanism of the diphenyl reaction, we have found that certain metals cause side 80 reactions to take place in the benzol vapor phase, the final result of which is the production of carbon and hydrogen. Our experience with fused salt baths indicates that these objectionable side reactions do not occur to so great an extent, and that consequently the benzol vapor may be maintained for a longer period of time at diphenyl forming temperatures without large quantities of carbon and hydrogen being formed. This 85 longer period of time permits the diphenyl forming reaction to approach substantial equilibrium.

Our method is preferably carried out as 90 illustrated in the accompanying drawing, in which

Fig. 1 is a flow sheet showing one means of carrying the invention into effect, and

Fig. 2 is a similar view showing a modified 95 manner of carrying out the invention. 100

Referring first to Fig. 1, benzol, which may be either in liquid or vapor form, is pumped through a coil of pipe which is immersed in a molten salt bath maintained by suitable external heating means at a temperature at which substantially no diphenyl is formed. This coil acts as a preheater and if the benzol is first introduced in a liquid form therein, it is vaporized soon after it enters the pipe, and passes thereafter as vapor through the coil, during which passage it absorbs heat from the walls of the pipe. The lower end of the coil is perforated and the vapor streams out and in rising through the molten salt, in physical contact therewith, agitates the bath in such a manner as to maintain a practically uniform temperature throughout the bath and reaches the temperature of the bath by the time it passes therefrom.

By employing a large mass of molten salt we are enabled to prevent overheating of the vapor due to the heat capacity of the bath, and by means of a thermocouple immersed therein to observe temperature changes which may occur and change the heating so as to supply additional heat or lessen the rate of heating as may be desired. We prefer to operate the preheater bath at a temperature of 600° to 650° C., and have found from experience that this is the optimum temperature range for continuous operation.

After the preheated vapor emerges from the preheater bath, it is immediately passed into a converter bath which is of similar design and arrangement as the preheater. The vapor passes to the bottom of the bath and streams out through holes in the distributor, and then bubbles up through the salt in a manner similar to the preheater. The converter bath is kept at a temperature range of from 750° to 850° C. When the vapor passes from the converter bath, it is passed to a condenser where the benzol and diphenyl are condensed while the hydrogen which is liberated is suitably vented to the atmosphere.

In view of the fact that we have found that metals, particularly iron, cause considerable carbon formation from benzol at diphenyl forming temperatures, it is desirable if iron apparatus is employed to so construct the passages and the condenser that rapid cooling of the vapor is effected. Furthermore, because of the fact that the use of molten salts particularly decreases the rate of carbon formation from benzol, it is possible to operate without a preheater, it being however desirable to vaporize the benzol first, although this is not absolutely necessary when operating at low rates.

In some instances it may be desirable to cool the benzol diphenyl vapors leaving the diphenyl converter, by passing them through a molten salt bath maintained at temperatures below the diphenyl forming temperatures. This method of operating is illustrated

in Fig. 2 of the drawing and is particularly desirable where the preheater and cooler may be combined in one unit. In this case the benzol vapors being preheated are passed through a continuous pipe 10 immersed in the preheating salt bath, then bubbled through a converter salt bath maintained at diphenyl forming temperatures, after which the vapors return to the preheating salt bath through a pipe 11, being now however bubbled through the molten salt itself. By working in this manner, the hot diphenyl containing vapors are caused to impart their excess heat to the molten salt of the preheater bath in a very effective manner, while the incoming benzol vapors acquire the heat given up by the outgoing gases. This method of working provides for the carrying out of the diphenyl reaction and the cooling of the vapor out of contact with metals, consequently avoids material loss through the formation of carbon, as well as effecting a considerable economy in heat recovered.

While we have shown our invention in but two forms, it will be obvious to those skilled in the art that it is not so limited but is susceptible to various other changes and modifications, without departing from the spirit thereof, and we desire therefore that only such limitations shall be placed thereupon as are imposed by the prior art, or as are specifically set forth in the appended claims.

What we claim is:

1. In a process of producing diphenyl, passing benzol vapors through a molten inorganic salt having a melting point less than the diphenyl forming temperature, and inert with respect to the benzol vapors and heated to a temperature at which substantial quantities of diphenyl are formed, and condensing the vapors.

2. In a process of producing diphenyl, passing benzol vapors through an inert molten salt bath, said salt having a density substantially less than 2.5, a melting point less than the diphenyl forming temperature, and heated to a temperature at which substantial quantities of diphenyl are formed, and cooling and condensing the vapor.

3. In a process of producing diphenyl, passing benzol vapor through a molten salt, said salt having a melting point less than the diphenyl forming temperature and inert with respect to the benzol vapor.

4. In a process of producing diphenyl, passing benzol vapor through a molten salt heated to diphenyl forming temperatures, and then through a molten salt heated to temperatures substantially less than diphenyl-forming temperatures.

5. In a process of producing diphenyl, passing benzol vapor through a preheater molten salt bath maintained at less than diphenyl forming temperatures and out of direct contact therewith, then through a molten

salt bath maintained at diphenyl forming temperatures, and then through said pre-heater bath in direct contact therewith.

In testimony whereof we, THOMAS E. WARREN and CHARLES B. DURGIN, affix our signatures.

THOMAS E. WARREN.
CHARLES B. DURGIN.
